UNITED STATES PATENT OFFICE.

JOHN D. GRABILL, OF WOODSTOCK, VIRGINIA.

GRADING MACHINE.

Application filed September 10, 1927. Serial No. 218,802.

This invention relates to improvements in grading machines and more particularly to grading machines for fruits and vegetables of the type in which a plurality of 5 endless traveling sizing chains are employed, arranged end to end in series.

In the use of grading machines of the class referred to that have a series of sizing chains disposed end to end, if it is desired to separate the fruit, vegetables or the like into a less number of grades than will be affected by the entire series of sizing chains, or to employ only certain chains of the series, it is necessary to completely remove the sizing chains not desired from the machine and to rearrange the remaining sizing chain units and the driving connections accordingly. As will be understood the removal, replacement, and rearrangement of 10 the sizing chain units and driving connections necessary in changing from the use of all to only certain of the series of sizing chains and vice versa, is a serious drawback in the use of the machine interchangeably in 15 this way to meet different demands as to the number and size of the grades required.

The object of the invention is to provide means of a simple, efficient, inexpensive nature that can be easily and quickly applied to a grading chain to close the sizing openings of the chain and convert the chain into a transfer belt or conveyor, and whereby a grading machine can be quickly changed to eliminate any one or more of its sizing 20 chains as regards the exercise of the sizing function thereof and permit of the use of any one of a series of sizing chains independently of or in combination with any of the others without removal of any of the sizing chain units from the machine or disturbing the chain driving connections, and without destroying the continuous character of 25 the machine.

The invention with other objects and advantages thereof, and the particular construction, combination and arrangements of parts comprising the same, will be understood from the hereinafter contained detail description, when considered in connection 30 with the accompanying drawings, forming part hereof and illustrating one embodiment of the invention.

In the drawings:

Figure 1 is a top plan view of a grading

machine having applied to one of its sizing 55 chains a cover member or device in accordance with the present invention.

Fig. 2 is a vertical longitudinal section.

Fig. 3 is a detail top plan, on a reduced scale and broken away, of the cover member 60 laid out flat.

Fig. 4 is a fragmentary top plan view, on an enlarged scale, of a sizing chain with the cover member applied thereto.

Fig. 5 is a detail view, on an enlarged 65 scale of a portion of the sizing chain and end portions of the cover member with means securing the same to the sizing chain.

The invention comprehends an endless flexible cover member for a sizing chain adapted 70 to be secured about the chain to close the sizing openings of the chain and to act with the chain as a conveyor belt or transfer means. More particularly, the invention contemplates a cover device comprising a strip of 75 flexible material of a length and width corresponding generally to that of the sizing chain and adapted to be arranged thereabout to extend over and close the sizing openings of the chain, and means for securing said cover strip to the sizing chain. The invention further comprehends the use of one or more of such cover devices in combination with a series of grading chains to eliminate 80 as desired one or more of the series of sizing chains as a sizing medium and to convert the same into one or more plane conveyor belts.

Referring to a detail description of the particular embodiment of the invention illustrated in the drawings, 1 designates the frame of the grading machine, the same being shown as comprising uprights 2 and upper and lower side rails 3-4. Mounted on the upper part of the frame 1 is a plurality of endless traveling sizing chains having different size grading openings, said sizing chains being arranged end to end in series progressively in accordance with the size of grading openings therein and with the sizing chain having the smaller size openings in advance. In this exemplification of the invention three of such sizing chains are shown, designated A-B-C.

The structure of the chains A-B-C, here shown, is the same as that illustrated in 105 my Patent No. 1,636,227 dated July 19, 1927, the chain structure comprising rigid transverse rod members 5 and series of interme-

diate longitudinal link members 6 pivotally connected therewith, said transverse rod members and link members being relatively arranged to provide similar size grading openings, as shown, throughout the chain, the link members 6 being spaced apart by sleeves 7 on the transverse rod members 5. At either side of the chain is a set of outer longitudinal link members 8 similar in construction to the series of link members 7 and pivotally connected to the outer end portions of the transverse rod members 5, the outer sets of link members 8 with the outermost of the series of link members 7 and the outer 15 end portions of the transverse rod members 5 constituting side sections to engage driving sprocket wheels. Spacing sleeves are provided between the longitudinal link members 8 and the outermost of the series of link members 7.

The supporting and driving means for the series of sizing chains A—B—C comprises pairs of rolls 9, 10, and sprocket wheels 11 located at either end of the rolls 9. The rolls 9 and sprocket wheels 11 are fixedly secured to shafts 12, 13, 14, and the rolls 10 fixed to shafts 15, the several shafts being mounted for rotation in suitable bearings on the frame 1. The sprocket wheels 11 project radially outward beyond the faces of the rolls 9 so that the sizing chains A—B—C engage the rolls 9, and the outer side sections of the chain including the outermost of the series of links 5, the outer links 8, and the end portions of the transverse rod members engage the sprocket wheels. 16 designates a motor mounted on the lower part of the frame 1 and connected by a belt 17 with a pulley 18 on one end of 25 the shaft 13 for driving the series of sizing chains, motion being transmitted from the shaft 13 to the shafts 12, 14, through the medium of sprocket chains 19, 20, engaging pinions 21, 22 on shafts 12, 14, and pinions 23, 24 on the shaft 13. 25 designates a hand crank adapted to be engaged with one end of the shaft 12, as shown, to provide for manually operating the series of chains, if desired. The machine is provided at its forward end with a hopper 26 and with a table 27 at its discharge end. 28 are side boards extending substantially the full length of the frame at either side of the sizing chains for holding the fruit, vegetables, or the like, on the chains. Associated with the several sizing chains A—B—C are laterally extending slatted transverse aprons 29.

30 designates the endless flexible cover member or device adapted to be secured on a sizing chain, to extend over and close the sizing openings of the chain and act with the sizing chain as a simple conveyor belt or transfer means. The endless flexible cover member or device 30 comprises a sheet of flexible material of a length and width

corresponding generally to that of the sizing chains A—B—C, adapted to be wrapped or arranged about the sizing chain, with its ends brought adjacent in the form of a band, and means for securing said cover member to the sizing chain to travel therewith. The endless flexible cover member 30 is preferably constructed of canvas or the like, but the same may be formed of any other material suitable for the purpose. Any appropriate means may be employed to secure the cover member 30 to the sizing chain. The means shown in the present instance for this purpose comprises series of eyelets 31 in the end portions of the cover strip 30, and ties 32 in the form of short sections of light rope, twine, or the like, the sections of rope or twine 32 being looped through the eyelets 31 of one end portion of the cover strip 30 (as illustrated in Figure 3 of the drawings). One of the looped ends 32^a of the rope sections 32 is carried around one of the series of longitudinal link members 7 and tied with the other free end 32^a. Following this one of the looped end portions 32^a is passed through one of the eyelets 31 of the other end portion of the cover strip 30 and the two free end portions 32^a finally tied together (as shown in Figure 5 of the drawings), the two end portions of the cover member 30 being thus secured together and to the sizing chain. The cover member 30 may be very quickly and easily arranged on and secured to the sizing chain by simply securing one end portion of the cover member to links 7, as previously explained, then transmitting movement to the series of sizing chains until the cover member 30 has been completely wrapped about the chain and the adjoining end portions of the cover member are at the upper side of the chain as shown in Figure 4 of the drawings. The other end portion of the cover member 30 can then be easily secured by the ties 32.

It has been found in practice that the securing of the cover member 30 at its end portions by the eyelets 31, and the ties 32, as hereinbefore explained, is sufficient to satisfactorily hold the cover member to the sizing chain. However under certain conditions, it may be desirable to also secure the cover member 30 at marginal side portions thereof to the sizing chain, and for this purpose the cover member may be provided, as shown, with eyelets 33 at intervals along its marginal side portions, and secured to the outermost of the series of link members 7 of the sizing chain by other ties 34.

In the operation of the machine, under ordinary conditions when all three of the sizing chains A—B—C are employed, the apples or the like are separated into four grades, the smaller size apples dropping

through the openings in the first size chain A, the intermediate sizes being carried respectively to chains B and C and dropping through the openings therein, and the 5 larger size apples being carried by the series of chains A—B—C to the discharge end of the machine to the table 27, the smaller and intermediate grades which drop through the openings of the sizing chains, 10 A—B—C, being delivered by the aprons 29 to one side of the machine.

When it is desired to separate the fruit, 15 vegetables or the like into a less number of grades, all that is necessary is to apply a cover member or cover members 30 to the sizing chains which it is desired to dispense with. In Figures 1 and 2 of the drawings, a cover member 30 is shown applied to the second chain B of the series of sizing chains. 20 As will be understood with this arrangement, the apples or the like which are too large to pass through the openings in the chain A are carried forward onto the covered chain B and transferred to the succeeding chain C, the chain B, in this instance, not functioning as a sizing medium but with its cover member 30 acting as a simple conveyor.

It will be noted that the invention provides 25 means of a simple inexpensive nature which can be quickly and easily applied to a sizing chain to close the openings therein and act therewith as a simple conveyor or transfer means so that a grading machine can be quickly changed to eliminate any one or more of its sizing chains as regards the exercise of the sizing function thereof, and providing for the use of any one of a series of sizing chains independently of or 30 in combination with any of the others without removal of any of the sizing chain units from the machine or disturbing the driving connections, and without destroying the continuous character of the machine.

40 While a specific embodiment of the invention, which has proven satisfactory in practice, is illustrated in the drawings, it will be understood that changes and modifications may be made in the particular construction shown, and the invention carried out in other forms of constructions, as will appeal to those skilled in the art and falling within the scope of the appended claims, without departing from the spirit of the invention. The flexible cover member or device 30 may of course be employed with various constructions of sizing chains, and the number of sizing chains and flexible cover devices may be varied as desired.

45 What I claim is:

1. In a grading machine, the combination with an endless traveling sizing chain and supporting and driving means therefor, of an endless flexible cover member for the 50 sizing chain adapted to be arranged thereon

to travel therewith and to close the sizing openings of the chain, and means for securing the cover member to the sizing chain.

2. In a grading machine, the combination with a series of endless traveling sizing chains and supporting and driving means therefor, of an endless flexible cover member adapted to be arranged on a sizing chain to travel therewith and to close the sizing openings of the chain, and means for securing the cover member to a sizing chain. 70

3. In a grading machine, the combination with a series of endless traveling sizing chains and supporting and driving means therefor, of a cover member comprising a strip of flexible material adapted to be arranged about a sizing chain to close the sizing openings of the chain, and means for securing the cover member to the sizing chain 80 for travel therewith.

4. In a grading machine, the combination with a series of endless traveling sizing chains and supporting and driving means therefor, of a cover member comprising a strip of flexible material adapted to be arranged about a sizing chain to close the sizing openings of the chain, and means for securing the cover member at its end portions to the sizing chain 90 for travel therewith.

5. In a grading machine, the combination with a series of endless traveling sizing chains and supporting and driving means therefor, of a cover member comprising a strip of flexible material adapted to be arranged about a sizing chain to close the sizing openings of the chain, and means for securing the cover member at its side marginal portions to side portions of the sizing chain. 100

6. In a grading machine, the combination of a series of endless traveling sizing chains and supporting and driving means therefor, of a cover member comprising a strip of canvas or the like adapted to be secured on a sizing chain to close the sizing openings of the chain and for travel therewith, said cover strip being provided at its end portions with fastening means for securing the same to the sizing chain. 105

7. In a grading machine, the combination with a series of endless traveling sizing chains and supporting and driving means therefor, of a cover member comprising a strip of canvas or the like adapted to be secured on a sizing chain to close the sizing openings of the chain and for travel therewith, said cover strip being provided at its side marginal portions with means for securing the same to side portions of the sizing chain. 115

8. In a grading machine, the combination with an endless sizing chain comprising rigid transverse rod members and series of intermediate longitudinal links pivotally connected to the transverse rod members and 130

spaced to provide grading openings of a similar size, and supporting and driving means for the sizing chain, of a cover member for the sizing chain comprising a strip 5 of canvas or the like adapted to be arranged about the sizing chain to close the sizing openings therein and for travel with the chain, said cover member being provided with eyelets along its end portions, and means 10 cooperating with said eyelets to secure the end portions of the cover member to longitudinal link members of the chain.

9. In a grading machine, the combination with an endless sizing chain comprising 15 rigid transverse rod members and series of intermediate longitudinal links pivotally connected to the transverse rod members and spaced to provide grading openings of similar size, and supporting and driving 20 means for the sizing chain, of a cover member for the sizing chain comprising a strip of canvas or the like adapted to be arranged about the sizing chain to close the sizing openings therein and for travel with the 25 chain, said cover member being provided with eyelets along its end portions, and ties cooperating with said eyelets to secure the end portions of the belt to longitudinal link members of the chain.

30 10. In a grading machine, the combina-

tion with an endless traveling sizing chain comprising rigid transverse rod members and series of intermediate longitudinal link members pivotally connected to the transverse rod members and spaced to provide 35 grading openings of similar size, and supporting and driving means for the chain, of a cover member for the sizing chain comprising a strip of canvas or the like adapted to be arranged about the sizing chain to close 40 the sizing openings thereof and for travel with the chain, said cover member being provided with eyelets along its side marginal portions, and means cooperating with said eyelets to secure the cover member at 45 side marginal portions thereof to the longitudinal link members of the chain.

11. A cover device for a grading chain comprising a strip of canvas or the like of a length and width corresponding to that 50 of a grading chain adapted to be arranged about the grading chain to close the sizing openings of the chain and act with the chain as a conveyor, and means for securing said cover strip to the sizing chain for travel 55 therewith.

In testimony whereof I hereunto affix my signature.

JOHN D. GRABILL.
